A. DARE.

DEVICE FOR TRANSMITTING SOUND WAVES.

APPLICATION FILED FEB. 24, 1908.

907,320.

Patented Dec. 22, 1908.

UNITED STATES PATENT OFFICE.

ARTHUR DARE, OF PHILADELPHIA, PENNSYLVANIA.

DEVICE FOR TRANSMITTING SOUND-WAVES.

No. 907,320.

Specification of Letters Patent.

Patented Dec. 22, 1908.

Application filed February 24, 1908. Serial No. 417,481.

To all whom it may concern:

Be it known that I, ARTHUR DARE, a citizen of the United States, residing at No. 1700 Walnut street, Philadelphia, in the county of Philadelphia and State of Pennsylvania, have invented certain new and useful Improvements in Devices for Transmitting Sound-Waves; and I do declare the following to be a full, clear, and exact description 5 of the invention, such as will enable others skilled in the art to which it appertains to make and use the same, reference being had to the accompanying drawings, and to the letters and figures of reference marked thereon, which form a part of this specification.

This invention relates to improvements in devices for transmitting sound waves of the human voice and is adapted for use in connection with the telephone, phonograph and 20 other like sound transmitting and recording instruments.

The invention embodies a device so constructed that when placed over the mouth the sound of speech will be muffled and rendered inaudible from without yet at the same time the sound waves set up in the larynx will be permitted to travel to the diaphragm of the recording or transmitting instrument released only from the pressure of exhaled air 30 from the lungs. This is accomplished by the employment of a mouth piece of ample size having pressure exits communicating with an expansion chamber of sufficient capacity to reduce the pressure and permit the exhaled air to pass out at a reduced pressure to 35 the atmosphere.

A further object of my invention is to absorb and prevent a reflex action of the diaphragm on the receiving side of the instrument by the employment of a double series of parallel non-resonant tubes which may be adjusted to and from each other to facilitate the intensity of sound in the transmission of long or short distance communications.

The nature of my invention will be best understood when viewed in connection with the accompanying drawings forming part of the specification and in which—

Figure 1 illustrates a side elevation of a 50 telephone transmitter constructed in accordance with my invention. Fig. 2 shows a horizontal section of the same as taken on a line indicated at 2—2 in Fig. 1. Fig. 3 is a vertical section taken on a line 3—3 of Fig. 2. Fig. 4 is a similar section taken at 4—4 of Fig. 2. Fig. 5 denotes a diagrammatic sec-

tion similar to Fig. 2 of a portion of the apparatus on a reduced scale showing a slightly modified form of expansion chamber and Fig. 6 shows a similar diagrammatic section 65 of the pipe leading to the diaphragm casing, the pipe in this instance being expanded to form an expansion chamber which is provided with discharge orifices as is the case with the form shown in Figs. 1 and 2. 65

Referring now to the letters indicating similar parts throughout the drawings, A, is the box or inclosure of a telephone containing the conventional diaphragm A¹ and contact button A². 70

B, is the transmitter box comprising conical chambers B¹ and B², the former of which is provided with a mouth piece B³, which is detachably secured in place by set screws b³, b³, etc. The conical chamber B¹ projects 75 into the chamber B² and is provided with a number of annular pressure exits b¹, b¹, etc., which form oblique or indirect lines of communication with the chamber B². The chamber B¹, is also provided with a flanged 80 opening B⁴, for the reception of a compact mass of small tubes b⁴, b⁴, etc. formed of rubber or a like non-resonant material. The chamber B² which is designed as an expansion chamber is provided with a number of 85 annular openings or pressure exits b², b², etc. through which exhalations of air are free to pass to the atmosphere. The reduced end of the conical chamber B², loosely surrounds 90 a pipe C, so that by operating a lever D, through its connecting link D¹, it will move the two chambers of the transmitter box 95 forward or backward upon the pipe C. The pipe C, is firmly secured to the box or casing A, containing the diaphragm and its connections and said pipe is filled at its forward end with a number of small tubes c¹, similar to the tubes b⁴ and made of a like non-resonant material. The lever D, by which the transmitter-box or slidale member of the device 100 is operated is fulcrumed to a bracket D² by a pin d², and by the link D¹, is fulcrumed at a point d¹, to a ring on the chamber B². 105

In using the instrument the operator places the mouth within the mouth piece B³ and in speaking the pressure due to the exhaled air from the lungs will be almost entirely eliminated by the free exit afforded by the openings b¹ and b², permitting the more delicate sound waves of speech to 110 pass through the non-resonant and parallel masses of tubes b⁴ and c¹ to the diaphragm A¹.

During a course of experimentation I have found that good results may be obtained by constructing the expansion chamber in the manner shown in Fig. 5 in which case the inclosing wall B^2 of the chamber is cylindrical as distinguished from the conical wall shown in the preferred form illustrated in Figs. 1 and 2. The pressure exits b^x , are here also modified being located between the chambers B^1 and B^2 , and not within the inclosing wall of said chamber, as is the case with the preferred form.

A further modification of my invention is illustrated in Fig. 6 in which case the expansion chamber proper of the preferred form is eliminated and the tube C thereof is expanded as shown at C^x to act in lieu of an expansion chamber and as shown is provided with a number of discharge openings c^{xx} , c^{xx} , etc.

It will be noted in Fig. 6 that a single system of tubes c^1 is employed and that the surrounding casing or main tube is devoid of a mouth piece it being preferred for sanitary reasons that the hand of the operator be used and interposed between the mouth and the tube in speaking. In order to accomplish the results with this single tube system as I have been able to accomplish by the double system of Figs. 1 and 2 *i.e.* the elimination of pressure other than that caused by speech, it is necessary that the tubes c^1 , c^1 , etc. should be bent at an angle as shown at c^x , which it has been found by experiment will to a very appreciable extent tend to dissipate the pressure due to the exhalation of air from the lungs which upon being deflected is released through the openings c^{xx} .

Having described my invention what I claim and desire to secure by Letters Patent is:

1. A telephone transmitter comprising two connected compartments one of which is fashioned to form a mouth piece and the other adapted to act as an expansion chamber, a series of non-resonant tubes arranged between the compartments, a pipe leading from the expansion chamber to the inclosure containing the diaphragm and a series of non-resonant tubes located within said pipe.

2. A telephone transmitter comprising

two compartments, the first of which is provided with side openings leading into the second compartment and the latter having side openings communicating with the atmosphere, a series of non-resonant tubes arranged between the compartments, a pipe leading from the second compartment to an inclosure containing the diaphragm and a second series of non-resonant tubes contained in said pipe.

3. A telephone transmitter comprising two connected conical chambers, a series of non-resonant tubes arranged between the chambers, a pipe leading from one of the chambers to an inclosure containing the diaphragm and its mechanism, and a series of non-resonant tubes arranged within said pipe.

4. A telephone transmitter comprising two connected chambers provided with an annular pressure exits, a series of non-resonant tubes interposed between said chambers, a pipe leading from one of the chambers to the inclosure containing the diaphragm, a series of non-resonant tubes contained in said pipe and means whereby the distance between the two series of non-resonant tubes may be increased or diminished.

5. A telephone transmitter comprising two connected conical chambers, the first of which is adapted to act as a mouth piece and the second as an expansion chamber, the first chamber being provided with annular openings communicating with the second chamber and the latter having similar openings forming communications from without, a series of non-resonant tubes interposed between the chambers, a pipe leading from the second chamber to a box containing the diaphragm and its mechanism, a series of non-resonant tubes contained within said pipe and means including a lever and connecting link for moving the chambers and consequently varying the distance between the non-resonant tubes.

In testimony whereof I affix my signature, in presence of two witnesses.

ARTHUR DARE.

Witnesses:
